UNITED STATES PATENT OFFICE.

HENRY G. VOIGHT, OF NEW BRITAIN, CONNECTICUT, ASSIGNOR TO THE AMERICAN HARDWARE CORPORATION, OF NEW BRITAIN, CONNECTICUT, A CORPORATION OF CONNECTICUT.

LOCK.

1,105,167.

Specification of Letters Patent. Patented July 28, 1914.

Application filed January 27, 1912. Serial No. 673,872.

To all whom it may concern:

Be it known that I, HENRY G. VOIGHT, a citizen of the United States, residing at New Britain, county of Hartford, State of Connecticut, have invented certain new and useful Improvements in Locks, of which the following is a full, clear, and exact description.

My invention relates to locks for operating electric switches located in door jambs, and has for its object to provide a lock having a two-part bolt, one part of which constitutes the dead bolt and embraces the other, so that when both parts are thrown it will have the appearance of a single part bolt, except for the dividing line, and further has for its object to provide mechanism whereby the dead bolt portion of the two-part bolt can be operated from the inside of the door independently of the inner or auxiliary portion of said bolt, and whereby both portions can be simultaneously thrown into locking position from the outside of the door.

The following is a description of an embodiment of my invention, reference being had to the accompanying drawings, in which—

Figure 1 shows a lock embodying my invention, with the face plate removed, and both parts of the bolt in retracted position. Fig. 2 shows the lower portion of this lock with the face plate removed and both portions of the bolt thrown into locking position. Fig. 3 shows a similar portion of the lock with the dead bolt portion of the bolt thrown into locking position and the inner portion in retracted position. Fig. 4 is a detail of the connecting bar by which one tumbler is lifted from the inside of the door. Fig. 5 is a side elevation and plan view of the auxiliary bolt tumbler. Fig. 6 is a side elevation and plan view of the dead lock bolt tumbler. Fig. 7 is an end view of the dead bolt. Fig. 8 is a side elevation of the same. Fig. 9 is a plan view of the same. Fig. 10 shows, in side elevation and plan view, the inner or auxiliary bolt. Fig. 11 shows an end view of a modification of the dead lock and auxiliary bolts.

Referring more particularly to the drawings, 1 is an electric switch having a normally extended actuating push-button 2, placed behind the strike plate 3 in the jamb of the door.

4 is the lock casing having the front plate

5. The plate 5 is provided with an opening for a dead bolt 6, said dead bolt having in its head an opening 7, which, when this bolt alone is thrown to outward position, embraces the push-button 2 of the electric switch. The tail end of this dead bolt is provided with projections 8 and 8', forming a notch whereby the bolt is actuated by arms 9 of a thumb-turn hub 10 from the inner side of a door. These arms 9 also engage a spring actuated lifting plate 10', which actuates a bar 11 embracing a projection 12 on a tumbler 13 pivoted to the case on the pin 14 and normally held in depressed position by the spring 15. This tumbler has a projection 16 which engages one side or the other of a projection 17 carried by the bolt 6. The dead bolt 6 is provided with two arms 18, within which lies an auxiliary bolt 19 having a slot 20 embracing the pin 14 so as to be movable relatively to the casing. This auxiliary bolt 19 is provided with a notch 21, which, when both bolts are thrown to retracted position, registers with a notch 22 in the bolt 6. Pivoted upon the pin 14 is a second spring actuated locking tumbler 23 having a projection 24, which engages one side or the other of a projection 25 on the auxiliary bolt 19.

When the bolts are both thrown to retracted or unlocking position, as in Fig. 1, and the key is inserted through the key-hole 26 and turned counterclockwise, the key lifts both of the tumblers 13 and 23, so that the projections 16 and 24 are disengaged respectively from the projections 27 and 25, whereupon a continued movement of the key engaging the notches 21 and 22 throws both bolts outward into the position shown in Fig. 2. A reverse movement of the key acts in a similar manner to lift the dogs 13 and 23 and throw both bolts inward to unlocked position. It will, therefore, be seen that when the key is used to lock the door, both bolts are thrown outward and the push-button 2 is moved from the position shown in Fig. 1 to the position shown in Fig. 2. If, however, with the parts in the position shown in Fig. 1, the thumb-turn hub 10 is turned clockwise, the first movement is for one of the arms 9 to lift the plate 10', thus lifting the bar 11 and lifting the single tumbler 13, so that the projection 16 will be disengaged from the projection 17. A continued movement of the thumb-turn hub then causes the other arm 9 to engage the

shoulder 8 and move the dead bolt 6 into locking position, as shown in Fig. 3, the inner or auxiliary bolt 19 being restrained from movement by the projection 24 of the 5 dog 23, said dog engaging the projection 25 of the bolt 19. It will thus be seen that when the lock is actuated by the thumb-turn hub 10, the dead bolt 6 alone is thrown, the inner or auxiliary bolt 19 being held in re- 10 tracted position, with the result that when the door is locked by turning the thumb-turn hub 10, the push-button 2 of the electric switch is not acted upon, but remains in extended position. A reverse movement of the 15 thumb-turn hub 10 acts in a similar manner to lift the tumbler 13 and to retract the dead bolt, so that the parts are restored to the position shown in Fig. 1. By this means, I provide a lock having a two part bolt, the 20 dead bolt portion of which is actuated from both the outside and inside, while both the dead and auxiliary bolt portions are actuated from the outside, whereby a switch in the door jamb will be thrown whenever the 25 door is locked from the outside, but will not be affected when the door is locked from the inside.

In the embodiment shown, whenever the door is locked from the outside by the key, 30 it cannot be unlocked from the inside by the thumb-turn hub, because the projection 24 will hold the bolt 19 against retraction. The flange 19' on the bolt 19 prevents the retraction of the bolt 6 when the bolt 19 is not retracted. Whenever the door is locked from the inside, the rear end of the inner bolt 19 will prevent the guest's key inserted from the outside, from turning in either direction so as to lift the dog 13 or dog 23 and retract 35 the bolt 6. This bolt 6, however, when thrown by the thumb turn can be retracted from the outside by a suitable master key.

I prefer to construct the dead bolt 6 with the outer or head portion formed as shown 40 in Fig. 7, so as to completely surround the outer or head portion of the auxiliary bolt 19. It is obvious, however, that any of the advantages of my invention can be obtained if the dead and auxiliary bolts have their 45 heads formed as shown in Fig. 11, that is, if the dead bolt has a U-shaped head 6' and the auxiliary bolt has a head 19' filling the space within the arms of the U. With this arrangement the dead bolt which is relied 50 upon to make engagement with the strike- plate when the door is locked from either the outside or the inside, fills the hole in the strike-plate, while the inner or auxiliary bolt being thrown when the lock is actuated 55 from the outside, actuates the push-button 60

2 at that time, and does not actuate it when the lock is actuated from the inside. 27 is the ordinary knob actuated latch.

While the embodiment shown and described is the preferred embodiment, my invention, as will be evident to those skilled in the art, permits of various modifications without departing from the spirit thereof or the scope of the appended claims.

What I claim is:

1. In a lock, the combination of a dead bolt and a secondary bolt, the head of the dead bolt embracing the head of the secondary bolt at the top and both sides thereof, with means for throwing both of said bolts 75 outward and inward together, and means for independently throwing said dead bolt outward and inward, said two means being accessible from opposite sides of the door respectively.

2. In a lock, the combination of a dead bolt and a secondary bolt, the head of the dead bolt embracing the head of the secondary bolt, with means for throwing both of said bolts outward and inward together, 85 and means for independently throwing said dead bolt outward and inward, said two means being accessible from opposite sides of the door respectively.

3. In a lock, the combination of a dead 90 bolt and a secondary bolt, the head of the dead bolt completely surrounding the head of the secondary bolt, with means for throwing both of said bolts outward and inward together, and means for independently throwing 95 said dead bolt outward and inward, said two means being accessible from opposite sides of the door respectively.

4. In a lock, the combination of a dead bolt and a secondary bolt, the head of the 100 dead bolt completely surrounding the head of the secondary bolt, with means for throwing both of said bolts outward and inward together, and means for independently throwing 105 said dead bolt outward and inward, said two means being accessible from opposite sides of the door respectively.

5. The combination of a dead bolt and an auxiliary bolt, the head of the dead bolt embracing the head of the auxiliary bolt, with 105 a key for throwing both of said bolts outward and inward together, and a thumb-turn hub for independently throwing said dead bolt outward and inward, said key and thumb-turn hub being operable from opposite 110 sides of the door respectively.

HENRY G. VOIGHT.
